UNITED STATES PATENT OFFICE.

CHARLES W. COOPS, OF TAUNTON, MASSACHUSETTS.

TOP-HOLDER FOR AUTOMOBILES.

No. 849,598.

Specification of Letters Patent.

Patented April 9, 1907.

Application filed April 20, 1906. Serial No. 312,757.

To all whom it may concern:

Be it known that I, CHARLES WILLIAM COOPS, a citizen of the United States, residing in Taunton, county of Bristol, and State of Massachusetts, have invented an Improvement in Top-Holders for Automobiles, &c., of which the following description, in connection with the accompanying drawings, is a specification, like letters on the drawings representing like parts.

This invention relates to a novel holder or device for preventing the top from jumping as an automobile, carriage, or any other pleasure vehicle or craft is being run and subjected to jolts, the device herein shown being adapted to coact with the bows when the top is thrown back or is in its open condition.

I have shown my bow-holder as applied to a set of bows such as represented in my pending application Serial No. 287,034, filed November 13, 1905; but my invention is applicable to any usual bows of any class of top.

My novel bow-holder includes a support for the under side of the lowermost bow of the set of bows forming the top when the top is thrown back and a pressure device that coacts with another bow, preferably the upper bow of the top, to retain the under bow seated with relation to the support.

The pressure device is preferably spring-controlled, and the support for the lowermost bow is preferably so constructed as to prevent lateral movement of the bow in the line of the length of the seat.

Figure 1 in side elevation represents an automobile-body of one form with the top down and its covering omitted. Fig. 2 shows the bows at one side of the top enlarged, and Fig. 3 is a section yet further enlarged in the line x.

The bows d d' d² d³ and their irons c c' c² c³ are and may be all as shown and described in my said application.

To the body B at or near its rear end I connect two stands g, one for the bows at each side of the body. Each stand receives a threaded stud g', (shown by dotted lines in Fig. 3,) that is extended inwardly from the support g², forming part of my bow-holder, said stud receiving a nut g³, by which to confine the support to the stand.

The support shown has an outwardly and upwardly turned hook g⁴, preferably provided with a raised projection g⁵, having a central recess, as shown by dotted lines, to

receive the central foot or projection from a socket e².

The upright portion of the support g² is represented as tubular and receives at its upper end a sleeve h, having a locking-notch h', said sleeve being screwed into the screw-threaded upper end of said tubular portion.

The part of the holder designated as the "presser" is represented as a rod m, having a locking-pin m' and bent outwardly, as at m², to sustain a foot or socket piece n, movable vertically through a screw m³. The point has a teat to enter the upper side of said foot or socket-piece resting on the upper side of the topmost bow d. The opposite end of the rod m is passed through the sleeve h, then through a spiral spring n', and the threaded part of said rod has screwed upon it a sleeved nut n³, the upper end of which contacts with the lower end of said spring, while the upper end of the spring contacts with the sleeve h, so that rotation of the nut n² compresses said spring more or less and causes the foot of the presser device m to act with greater or less strength on the upper side of the uppermost bow of the open top, and in this way the bows of the top are held between the presser and the support and are retained pressed closely together in such position by the force of the spring n'.

The sockets e² and e between the adjacent bows are common to my said application and need not therefore be herein further described.

To raise the top, the foot-sustaining device will be manipulated to release the foot from the bow d and the rod m be turned to remove the portion n from above the bow d, and thereafter the spring n' will immediately depress the rod m until the pin m' enters the notch h' of the sleeve h, thus locking the rod in its in-operative position.

A top held as described cannot wobble or jump.

I provide each bow d d² d³ at its upper side with a socket-piece e, and the under side of each bow has a projection e², that coacts with the socket-piece, to prevent any lateral movement of the bows one on the other. The devices for preventing lateral movement of the bows would act just the same should the parts e and e² be transposed.

The support has a boss f, provided with a projection f', (see Fig. 3,) threaded at its end to receive a nut f². The unthreaded part of the projection f receives the holes at the end

of the rod *r*, (shown in dotted lines, Fig. 1,) said rod constituting the end member of a pair of such rods forming a top prop joint of usual construction.

Having described my invention, what I claim as new, and desire to secure by Letters Patent, is—

1. A bow-holder comprising a support for the lower bow, and a spring-controlled presser 10 coacting with the upper bow.
2. A bow-holder comprising a support for the lower bow, and a presser having a spring acting normally to cause the presser to engage the top bow.
3. The combination with a bow-holder and a support for the lower bow of a projection adapted to engage a recess and prevent lateral movement of said bow in said support.
4. A bow-holder comprising a support to 20 sustain and partially surround the lower bow of a set of bows, a rod having a foot, a spring acting normally to maintain said foot against a bow, and means to adjust the foot on said rod.

5. A bow-holder, a support for the lower bow, a presser having a coacting spring, and means to change the stress of said spring.

6. A bow-holder comprising a support and a yieldingly-sustained presser adapted to grasp between them a set of bows of a carriage-top, said presser being capable of being turned into its inoperative position when the carriage-top is up and in use.

7. A series of bows, a support for the lower-most bow of the series, a device acting to retain said bows from jumping with relation to said support when the top is thrown back, and means coacting with and intermediate said bows to prevent lateral movement thereof.

In testimony whereof I have signed my name to this specification in the presence of two subscribing witnesses.

CHAS. W. COOPS.
